UNITED STATES PATENT OFFICE.

JOSEPH G. BERTHIAUME AND ARTHUR E. BARLOW, OF WORCESTER, MASSACHUSETTS,
ASSIGNORS OF ONE-HALF TO WRIGHT WIRE COMPANY, OF WORCESTER, MASSACHUSETTS, A CORPORATION OF MASSACHUSETTS.

IMPLEMENT FOR APPLYING CLAMPS TO WIRE FENCES.

No. 880,712.

Specification of Letters Patent.

Patented March 3, 1908.

Application filed April 18, 1906. Serial No. 312,397.

To all whom it may concern:

Be it known that we, JOSEPH G. BERTHIAUME and ARTHUR E. BARLOW, citizens of the United States, residing at Worcester, in the

5 county of Worcester and State of Massachusetts, have invented a new and useful Implement for Applying Clamps to Wire Fences and the Like, of which the following is a specification.

10 Our invention relates to an implement especially designed for applying sheet metal clamps to fences and other fabrics but it is capable of general use for exerting pressure in a certain way. The particular kind of 15 fence to which it is especially adapted is made by placing a bent clamp or clip over one wire, passing the other wire through slots in the clip, and then flattening out the clip in such a manner as to off-set both wires 20 and form a stiff joint.

The principal objects of the invention are to provide means for performing this operation which will be convenient in operation, simple in construction, durable and substantial, and to avoid the decrease of the 25 throw of the jaw which takes place in implements which are now used for this purpose after they have been used for some time.

30 Reference is to be had to the accompanying drawings in which,

Figure 1 is a side elevation of an implement constructed in accordance with the principles of our invention. Fig. 2 is a 35 similar view on an enlarged scale with parts removed to show interior construction. Fig. 3 is a bottom plan view. Fig. 4 is a perspective view of a link which we prefer to employ. Fig. 5 is a perspective view showing the clamp or clip applied to the wires and ready to be operated upon by this implement, and Fig. 6 is a front elevation of the same.

We have shown the implement as comprising a body *a* from which extends an offset projection *a'*, provided with a jaw *b*. This jaw extends from the projection toward and beyond the center line of the body *a* and is provided with a groove *b'* for receiving one 45 of the wires of the fence. The off-set of the projection *a'* is for the purpose of accommodating the wire passing through this groove and permitting the same to be approached by the tool and the tool to be with-

drawn. The projection *a'* is provided with 55 a depression *a''* on its inner surface to receive the edge of the clamp or clip 10 upon which the implement operates.

For the purpose of engaging the clamp or clip and forcing it into the proper position, 60 a movable jaw *c* is mounted opposite the stationary jaw *b*. This movable jaw is provided with a groove *c'* which has an off-set portion *c''* to permit a bend in the wires of the fence to allow them to pass over the 65 transverse wires. The jaw *c* is mounted on a slide *d*. This slide works in ways *e* on the body *a*. The body is provided with a rearwardly extending projection or stationary arm *f* which has a handle *f'*. A lever *g* extends in the same general direction as the projection *f*. It carries a handle *g'* adapted to coöperate with the handle *f'*. The lever *g* is pivoted on a stud *h* and it is provided with a forwardly extending portion *g''* which 70 is pivotally connected with a link *k* which in turn is pivotally connected with the slide. It will be seen that the swinging of the lever *g* about its pivot will, through the instrumentality of the link, force the slide and 75 movable jaw forward and back with a great leverage. In the present instance, we have shown the link as being provided with two cylindrical or spherical ends *k'* which fit in corresponding sockets *g''* and *d'* in the arm 80 *g''* of the lever and the rear of the slide. Covering these elements is a plate *m* which is secured to the body of the implement.

By constructing a tool in accordance with the principles set forth above, whether in the 90 form shown or otherwise within the limits of our claims, an implement is secured which while giving a great leverage, is not susceptible to any changes due to wearing of the bearing surfaces.

95 It will be noted that when the parts are positioned, as shown in full lines in Fig. 2, the two axes on which the heads of the link are pivoted and the center of the pivot *h* are nearly in alinement but not quite so; in other words, the entire throw of the lever is not taken up and as the center one of these three points is slightly out of alinement with the other two, when the lever is moved toward the dotted line position, the parts will be 100 drawn back in an obvious manner, there being no dead center to overcome.

105 We are aware that many changes may be

made in the implement by any person skilled in the art without departing from the scope of our invention as expressed in the claims.

Having thus fully described our invention, 5 what we claim and desire to secure by Letters-Patent is:—

1. In an implement for applying clamps to wire fences and the like, the combination of a body having an arm, a handle on said arm, a 10 jaw located on the body opposite the arm, a second jaw adapted to move toward and from the first-named jaw, a slide on which the second jaw is mounted, said body having ways along which the slide is adapted to 15 move, said slide having a socket, a lever pivotally mounted with respect to the body and having a handle adapted to move towards and from the first-named handle, said lever having its socket located on the side of its 20 pivot opposite to that on which its handle is located, and a link having means located in said sockets by which said link is pivotally connected with the lever and with the second jaw, the points at which the link is pivot- 25 ed to the lever and to the jaw and at which the lever is pivoted to the body being substantially in alinement when the jaw is at the end of its stroke.
2. An implement for applying clamps to 30 wire fences and the like, comprising a body having a stationary arm, a handle on said arm, a stationary jaw located on said body opposite said arm, a movable jaw on the body, a lever pivoted to the body, a link piv-

otally connected with the lever and with the 35 movable jaw, and a handle on said lever adapted to move toward and from the first named handle, the points at which the link is pivoted to the jaw and to the lever and at which the lever is pivoted to the body being 40 nearly in alinement when the jaw is at the end of its stroke, the lever and arm being nearest together at the same time.

3. In an implement of the character described, the combination of a body having a 45 stationary arm provided with a handle and a stationary jaw, a second jaw adapted to move toward and from the stationary jaw, a slide on which the second jaw is mounted, said body having ways along which the slide 50 is adapted to move, said slide having a socket, a lever pivotally mounted on the body and having a handle adapted to move toward and from the first-named handle, said lever having a projection provided with a socket located on the side of its pivot opposite to that on which its handle is located, and a link having two cylindrical heads, one located in each of said sockets.

In testimony whereof we have hereunto 60 set our hands, in the presence of two subscribing witnesses.

JOSEPH G. BERTHIAUME.
ARTHUR E. BARLOW.
